ATOMIZER

William Spencer Bowen, Westfield, N. J.

Application December 23, 1937, Serial No. 181,273

6 Claims. (Cl. 299—63)

The present invention relates to atomizers and, more particularly, to spray heads of the rotatable type adapted to disperse a stream of liquid as a fine mist or spray. More specifically, 5 the invention relates to a new form of such spray heads whereby the liquid is atomized in an improved fashion.

While atomizers of the rotatable spray head type are well known to the art, existing forms of 10 this device present many inherent defects. A source of considerable dissatisfaction lies in the formation of the surface of such spray heads resulting in obstructions to the release of the atomized liquid. In existing forms, these obstructions cause a backing up of the product upon 15 the surface of the spray head, thereby interfering with the operation and, more specifically, the efficiency, of the device. Another defect in existing forms of this device is the lack of controlling 20 means to direct the flow of the atomized liquid. It is a desideratum to impart a downwardly and outwardly directional movement to the spray as well as to effect a concentration thereof.

In view of the deficiencies in the prior art relating to atomizers, it is an object of this invention 25 to provide a spray head so formed that there will be no backing up of the product on the surface thereof.

Another object of the invention is to provide in 30 a spray head of the type described, a construction whereby the atomized liquid may be given a suitable direction and concentration.

A further object of the invention is to provide a spray head to accomplish the above named objects which is of simple and economical construction.

According to one embodiment of the invention, a spider of some suitable material such as 35 duralumin is formed with a hub adapted to be secured to a drive shaft whereby the device may be rotated, said spider having a downwardly and outwardly extending flange at its periphery and having formed thereon spaced arms extending upwardly and outwardly. A deflecting member 40 in the form of a truncated cone is secured to the arms of the spider in such a manner that its elements are substantially parallel to the corresponding elements of the flange. The upper surface of the spider is formed so that all 45 portions thereof are at an angle to the central axis of the device. In operation, a stream of liquid is directed against the upper surface of the spider substantially at the center thereof, and the impact of the stream under centrifugal 50 force against portions of the rotating head op-

erates to atomize the liquid, said atomized liquid being thrown outwardly and downwardly through the openings between the arms of the spider and between the flange on the spider and the overhanging deflecting member. The above 5 described construction of the upper surface of the spider provides for the free escape of the atomized liquid so that no backing up thereof results.

The novel features considered characteristic of 10 the invention are set forth with particularity in the appended claims. The invention itself, however, both as to its construction and its method of operation, together with additional objects 15 and advantages thereof, will best be understood from the following description of a specific embodiment when read in connection with the accompanying drawing, in which:

Figure 1 is a plan view of the spray head with 20 a portion thereof cut away;

Figure 2 is a cross sectional view of the spray head taken along a line corresponding to the line 2—2 of Figure 1 and looking in the direction of the arrows.

Referring to the above drawing, in which like 25 numbers are used to designate like parts throughout, and without limiting the invention to this particular form, a spider 1 is formed with a hub 2 and upwardly and outwardly extending arms 3. The hub 2 is formed with a centrally 30 located aperture 7 and bushing 6 to receive a drive shaft, not shown in the drawing. The upper surface of the spider includes a flat portion 4 adjacent the said aperture 7 substantially at right angles to the central axis, a recessed portion 5 adjacent the said portion 4 also substantially at right angles to the central axis, and a downwardly and outwardly extending portion 35 provided by a flange 8. The inner surface 9 of the arms 3 is everywhere oblique to the central 40 axis. The ends of the arms 3 are machined to abut against a deflecting member 10 in the form of a truncated cone adapted to be secured thereto. Tap holes 11 are formed in the ends of the arms to receive screws 12 which extend through 45 openings 13 in the shield and which are fitted with suitable lock washers 14. The deflecting member 10 is secured to the arms 3 in such a position that the upper portion thereof overhangs the upper surface of the spray head and 50 the lower portion extends beyond the periphery of the spider 1.

The mode of operation of the device will be apparent from the above description. The spray-head is secured to a drive shaft as stated and is 55

rotated thereby. A stream of liquid is directed against the upper surface at or near the center, and is atomized by the impact and the rotation of the head. The rotation of the head operates 5 to give the atomized liquid an outward direction, said atomized liquid escaping downwardly and outwardly through the openings provided by the arms 3 and between the deflecting member 10 and flange 8.

10 It will be seen that a spray head as described above provides considerable improvement in the art. One advantage of the construction shown is that the upper surface of the spray head permits the free flow of the atomized liquid so that 15 no backing up thereof will result. Another advantage is that the combined use of a flange and overhanging deflecting member provides a control whereby the atomized liquid is directed downwardly and outwardly. A further advantage of the invention is that it provides the above named advantages in a construction which is 20 simple and economical.

Although a certain specific form of the invention has been shown and described, many modifications thereof are possible and will suggest themselves to persons skilled in the art. The invention, therefore, is not to be restricted except insofar as is necessitated by the prior art and by the spirit of the appended claims.

30 I claim:

1. In an atomizer of the rotatable spray-head type, a spider comprising a hub formed with upwardly and outwardly extending arms adjacent the periphery thereof, said hub being adapted to 35 be secured to a drive shaft and having all portions of its upper surface formed at an angle to the central axis, and said arms being formed with inner surfaces oblique to the said central axis.

2. In an atomizer of the rotatable spray-head type, a spider comprising a hub formed with upwardly and outwardly extending spaced arms, said hub having all portions of its upper surface formed at an angle to the central axis, inner surfaces on said arms formed at an angle to the 45 said central axis, a deflecting member in the form of a truncated cone on the said arms, said deflecting member having its upper portion overhanging the upper surface of the hub and its lower portion extending beyond the periphery of the hub and beneath the upper surface thereof.

50 3. An atomizer of the rotatable spray-head type comprising a spider having a hub formed with spaced outwardly and upwardly extending arms, said hub having all portions of its upper surface formed at an angle to the central axis,

55

inner surfaces on said arms formed at an angle to the said axis, a flange on the hub, means to secure the hub to a drive shaft, a deflecting member in the form of a truncated cone, and means to secure the deflecting member to the 5 arms of the hub, said deflecting member being positioned substantially in parallel relationship with respect to the flange.

4. In an atomizer of the rotatable spray-head type, a spider comprising a hub, means to secure the hub to a drive shaft, spaced supporting arms extending upwardly and outwardly, a flange extending downwardly and outwardly, said spider having an upper surface including a portion at the hub substantially at right angles to the central axis, a recessed portion adjacent the said hub portion substantially at right angles to the central axis, a curved portion oblique to the central axis formed by the arms of the spider, and a portion oblique to the central axis formed by 20 the flange on the spider.

5. An atomizer of the rotatable spray-head type comprising a spider having a hub formed with spaced outwardly and upwardly extending arms adjacent the outer periphery thereof, said hub having all portions of its upper surface formed at an angle to the central axis, inner surfaces on said arms formed at an angle to the said axis, a flange on the hub, means to secure the hub on a drive shaft, a deflecting member in the form of a truncated cone, and means to secure the deflecting member to the arms of the hub, said deflecting member being positioned with its 35 upper portion overhanging the upper surface of the hub and its lower portion extending beyond 40 and beneath the periphery of the hub.

6. An atomizer of the rotatable spray-head type comprising a spider having a hub formed with spaced upwardly and outwardly extending arms at the outer periphery thereof, said hub having all portions of its upper surface formed at an angle to the central axis, a flange on the hub extending downwardly and outwardly, means to secure the hub on a drive shaft, a deflecting member in the form of a truncated cone, adapted 45 to be positioned by the arms of the spider, and means to secure the deflecting member to the arms, said deflecting member being positioned substantially parallel to the flange on the hub with its upper portion overhanging the upper 50 surface of the hub and its lower portion extending beyond and beneath the periphery of the hub.

WILLIAM SPENCER BOWEN.
